UNITED STATES PATENT OFFICE.

WINTER W. CHRISTIAN AND AUGUSTUS G. MAXEY, OF OWENSBORO, KENTUCKY; SAID CHRISTIAN ASSIGNOR TO SAID MAXEY.

COMBINED LETTER BOX AND CHANGEABLE SIGN.

Application filed September 14, 1921. Serial No. 500,537.

To all whom it may concern:

Be it known that we, WINTER W. CHRISTIAN and AUGUSTUS G. MAXEY, citizens of the United States, residing at Owensboro, 5 in the county of Daviess and State of Kentucky, have invented certain new and useful Improvements in Combined Letter Boxes and Changeable Signs, of which the following is a specification.

10 Our invention relates to house letter boxes and has for its object the provision of a cheap and efficient durable receptacle having associated therewith means whereby the householder may display announcements 15 whereby passers-by may be given certain information. The invention is illustrated in the accompanying drawings and will be hereinafter fully set forth.

In the drawings—

20 Figure 1 is a perspective view of a device embodying our invention;

Fig. 2 is a vertical transverse section of the same;

25 Fig. 3 is a horizontal section on the line 3—3 of Fig. 2.

In carrying out our invention, we employ a back plate 1 which will preferably be of sheet metal and is provided at its upper and lower ends with openings 2 through which 30 suitable fastening devices may be inserted to secure the device to a fixed support. The side edges of the back plate are doubled upon themselves to form re-entrant flanges 3 and the side plates 4 of the device have 35 their rear side edges bent outwardly, as shown at 5, presenting flanges which are adapted to engage within the re-entrant flanges 3 whereby the side plates will be held to the back plate, and to prevent dropping of the side plates, the lower end of the flanges 3 are crimped, as indicated at 6, whereby they will be closed and will present shoulders upon which the lower ends of the flanges 5 may rest. The front side edges 40 of the side plates are bent outwardly, as shown at 7, and these outwardly bent flanges are engaged within the re-entrant flanges 8 formed at the longitudinal side edges of the front plate 9. The front plate is provided 45 with an opening 10 therethrough, and at a convenient distance above the said opening, a stop flange 11 is secured upon the back of the front plate, the said stop flange being adapted to bear upon the upper face of a 50 division plate 12 which is fitted between the

side plates 4 and has its ends turned downwardly at a right angle to provide flanges 13 riveted or otherwise rigidly secured to the said side plates. The division plate 12 constitutes the bottom of the mail box and also 60 serves as a connecting brace to prevent collapse of the structure. A similar plate 14 is fitted between the side plates 4 and between the lower end of the front plate 9 and the back plate, as shown clearly in Fig. 2, 65 and is secured to the said side plates in the same manner as the division plate 12 is secured thereto. The space defined by the front plate, the back plate and the upper and lower plates 12 and 14 constitute a chamber 70 to house a shiftable exhibitor consisting of an endless apron or belt 15 carried by rollers 16 and so located that announcements painted, printed, or otherwise placed upon the belt may be readily viewed through the opening 10 in the front plate. The said opening 10 is preferably covered by a pane 75 of glass or other transparent material, indicated at 17, and supported by a rim or flange 18 secured in any convenient manner upon the back of the front plate. The rollers 16 are equipped at their ends with pins 19 which may be engaged in slots or notches 20 formed in the side plates 4 and preferably inclined in opposite directions so that the 80 tendency of the rollers to seek the lower ends of the respective slots or notches will serve to maintain the display belt in a taut condition. The upper roller 16 has a knob or handle 21 fitted upon one of its journal pins 85 exteriorly of the adjacent side plate so that by rotating the said knob, the belt may be shifted to bring any desired announcement into alignment with the display opening 90 10. In the drawings, we have illustrated the device as displaying the announcement "No rooms," thereby indicating that the householder cannot accommodate any additional tenants. It will be understood that various announcements may be placed upon the display belt and any desired announcements easily brought into position to be read through the display opening by manipulation of the knob or handle 21.

105 The chamber or space above the division plate 12 constitutes a letter box into which mail may be placed through the upper end thereof and the name and route number of the householder or owner of the box may be 110 appropriately displayed upon the front plate 110

9, as will be readily understood. To protect mail against the weather elements, a cover 22 is provided and this cover, as well as all the other parts of the device, may be and 5 preferably will be of sheet metal. Flanges 23 are formed at the end edges of the cover and along the front edge thereof to depend over the upper end of the mail box so that rain and snow cannot readily obtain access to 10 the mail. The cover is mounted upon the back plate by a hinge 24 so that it may be easily raised when mail is to be placed in or taken from the mail box.

It will be readily seen from the foregoing 15 description, taken in connection with the accompanying drawings, that we have provided a very simple, inexpensive and durable device which will facilitate the delivery of mail and will enable a householder to 20 display desired announcements. The device may be manufactured at a very low cost and may be shipped in a knocked down position so that large quantities may be transported within a small space, and the 25 device may be readily set up in position for use by an unskilled person.

Having thus described the invention, what is claimed as new is:

A device for the purpose set forth comprising a back plate adapted to be secured 30 to a fixed support and having re-entrant flanges along its longitudinal side edges, the lower ends of said flanges being closed, side plates provided at their rear side edges with outstanding flanges to engage in the re-entrant flanges of the back plate whereby the side plates will be supported by the closed 35 lower ends of said re-entrant flanges, outstanding flanges at the front longitudinal edges of the side plates, a front plate having re-entrant flanges engaging the outstanding flanges at the front edges of the side plates, a division plate secured rigidly to and extending between the side plates, and a stop flange on the rear face of the 40 front plate adapted to bear upon said division plate whereby to support the front plate.

In testimony whereof we affix our signatures.

WINTER W. CHRISTIAN. [L.S.]
AUGUSTUS G. MAXEY. [L.S.]
